STACY B. HASELTINE, OF CHICAGO, ILLINOIS, ASSIGNOR TO WILLIAM H. MINER, OF CHAZY, NEW YORK.

KEYLESS DRAFT-RIGGING YOKE.

1,286,306.

Specification of Letters Patent.

Patented Dec. 3, 1918.

Application filed April 13, 1916. Serial No. 90,839.

To all whom it may concern:

Be it known that I, STACY B. HASELTINE, a citizen of the United States, residing at Chicago, in the county of Cook and State of Illinois, have invented a certain new and useful Improvement in Keyless Draft-Rigging Yokes, of which the following is a full, clear, concise, and exact description, reference being had to the accompanying drawings, forming a part of this specification.

This invention relates to improvements in keyless draft rigging yokes.

For several years past, the railroads have been desirous of obtaining a draw-bar and yoke connection which will avoid slotting of the sills and at the same time be readily detachable. Furthermore, the railroads are demanding a yoke connection of the above 20 character which is adapted to all types of standard draw-bars whether the latter have coupler key slots or not. A further requisite demanded by the railroads is a detachable draw-bar and yoke connection so arranged 25 that all the parts are easily accessible and wherein the draw-bar may be removed or replaced without disturbing the gear proper.

The object of my invention is to provide a yoke for railway draft riggings of simple 30 construction and which will embody all the advantageous features above indicated.

In the drawing forming a part of this specification, Figure 1 is a part side elevation, part longitudinal section of a yoke embodying my improvements, Fig. 2 is a horizontal sectional view of the yoke illustrated in Fig. 1 and taken substantially on the line 2—2 thereof. Fig. 3 is a transverse vertical section taken substantially on the line 3—3 of Fig. 1. Fig. 4 is a detail perspective of the locking block which I employ. And Fig. 5 is a view similar to Fig. 1 illustrating my improvements adapted to a tandem yoke.

Referring to said drawing, 10 denotes a standard draw-bar having the usual butt 11 provided with upper shoulder 12 and lower shoulder 13. The yoke A, which as shown is preferably a steel casting, is provided 50 with upper arm 14, lower arm 15, rear connecting piece 16, and a hollow, boxlike hood or head 17 at its front end, the hood being open at the front and provided with side walls 18—18, and upper wall 19, the upper wall 19 being provided on its inner face

with an integral, transversely extending gib or shoulder 20, the latter being adapted to coöperate with the upper shoulder 12 of the draw-bar. Within the yoke a shock absorbing member is illustrated conventionally 60 by dotted lines, the shock absorber shown in the drawing being a well known type of friction gear.

The hooded end of the yoke is provided in the bottom thereof with an enlarged recess 21 through which is insertible and removable a locking block 22 the latter having an upstanding angular shoulder 23 at its front end which is arranged to coöperate with the lower shoulder 13 of the draw-bar. To suitably brace the block 22 in draft movement of the gear the side walls 18 of the hood are provided with integral, inwardly extended shoulders or abutments 24, there being sufficient clearance therebetween 75 to permit the insertion and removal of the draw-bar. To support the block 22 in place, I have provided a key 25 which is of substantially the same width as the block 22. The key 25 has an elongated horizontally 80 extending arm 26 which passes through a slot 27 in the depending flange 28, beneath the block 22, and finally at its front end into a recess 29 formed in the transversely extending wall 30. The key 25 has a downwardly extended arm 31 at its rear end by which it is adapted to be held in place as by means of the bolt 32 which passes therethrough and through a corresponding perforation in the depending flange 28. In 90 order to minimize tendency of the key to bend under the weight of the locking block and draw-bar, the side walls of the hood are provided with inwardly extending, substantially rectangular ledges or shelves 95 132—132, see Fig. 3, on which the key is supported. On account of the shoulders 32—32, the locking block 23 is correspondingly recessed on its sides as indicated at 33—33 so as to permit the block to be inserted and removed.

To disassemble the parts, the bolt 32 is first removed after which the key 25 is withdrawn. Thereupon, the block 22 is lowered through the opening and the draw-bar may 105 then be lowered and withdrawn from the front end of the yoke.

In the construction illustrated in Fig. 5, the yoke A' and the means for locking the draw-bar in place are similar to those illus- 110

trated in Figs. 1 to 4, except that the yoke A' is provided with upper and lower transversely extending shoulders 40-40 at the inner end of the draw-bar so that the latter 5 will force the yoke rearwardly under buff and cause the yoke to act as a tandem yoke.

Although I have herein shown and described what I now consider the preferred means of carrying out my invention, the 10 same is merely illustrative and I contemplate all changes and modifications that come within the scope of the claims appended hereto.

I claim:

- 15 1. A yoke having parallel arms and provided with a hooded forward end integrally connecting said arms, said hooded end being adapted to receive a shouldered draw-bar butt therewithin, said yoke being provided with means arranged to engage the upper shoulder of a draw-bar butt, and devices coöperable with the lower shoulder of a draw-bar butt, for detachably locking the yoke to a draw-bar, said devices including 20 25 30 35 a shouldered locking block removable from below through an opening in the bottom of said hooded end, and a key for supporting said block, the walls of said hood having ledges on which said key is supported.
2. A keyless yoke having a hooded forward end, said hooded end being provided with an opening through the bottom wall thereof, a block insertible through said opening and having a shoulder adapted to engage the lower shoulder of a draw-bar

butt, the side walls of said hooded end having shoulders projecting into said recess and said block having the sides thereof recessed to correspond with said shoulders, and means for supporting said block in operative position. 40

3. A keyless yoke having a hooded forward end, said hooded end being provided with an opening through the bottom wall thereof, a block insertible through said opening and having a shoulder adapted to engage the lower shoulder of a draw-bar butt, the side walls of said hooded end having shoulders projecting into said recess and said block having the sides thereof recessed to correspond with said shoulders, and means for supporting said block in operative position, said means including a flat key on which said block rests, the key in turn resting upon said shoulders on the side 50 55 walls.

4. A keyless yoke having an integral hood at its front end, the bottom wall of the hood having an opening therethrough, a locking block insertible through said opening, and a key for supporting said block in position, said key comprising a wide flat member having a down turned flange, said key being insertible through a slot in the lower portion of the hood. 60 65

In witness that I claim the foregoing I have hereunto subscribed my name this 15th day of March 1916.

STACY B. HASELTINE.
